SPRINKLER BASE

John D. Beinert, Babylon, N.Y., assignor to Melnor Industries, Inc., Moonachie, N.J., a corporation of New York

Continuation of design applications Ser. No. 56,606, June 30, 1959, and Ser. No. 57,217, Aug. 18, 1959. This application Apr. 22, 1960, Ser. No. 60,332

Term of patent 7 years

(Cl. D91—1)

FIG. 1

FIG. 2

FIG. 3

FIG. 4

FIG. 5

FIG. 6

FIG. 7

FIG. 8

Fig. 1 is a top plan view of a sprinkler base showing my design;

Fig. 2 is a side elevational view of the sprinkler base of Fig. 1;

Fig. 3 is an end elevational view taken from the left hand end of Fig. 1;

Fig. 4 is an end elevational view taken from the right hand end of Fig. 1;

Fig. 5 is a side elevational view of a modified form of the sprinkler base shown in Figs. 1-4 inclusive;

Fig. 6 is an elevational view thereof as seen from the left of Fig. 5;

Fig. 7 is an elevational view thereof as seen from the right of Fig. 5; and

Fig. 8 is a top plan view of the embodiment of Fig. 5. This application is a continuation of my prior applications Ser. Nos. D. 56,606, filed June 30, 1959, and D. 57,217, filed August 18, 1959, both now abandoned.

I claim:

The ornamental design for a sprinkler base, as shown and described.
